UNITED STATES PATENT OFFICE.

THOMAS P. RUANE, OF FAIRCHANCE, PENNSYLVANIA.

RAM-SHOVEL FOR PULLING AND CLEANING BEEHIVE COKE-OVENS.

1,291,165.

Specification of Letters Patent. Patented Jan. 14, 1919.

Application filed May 16, 1918. Serial No. 234,937.

To all whom it may concern:

Be it known that I, THOMAS P. RUANE, a citizen of the United States, residing at Fairchance, in the county of Fayette and 5 State of Pennsylvania, have invented a new and useful Ram-Shovel for Pulling and Cleaning Beehive Coke-Ovens, of which the following is a specification.

This invention has reference to a ram 10 shovel for pulling and cleaning bee-hive coke ovens, and its object is to provide a device which will not only pull the coke but will clean the oven and thereby save manual labor which has heretofore been employed for the 15 purpose, and will more effectively and more expeditiously perform the operation with a material saving in cost and time.

In accordance with the invention there is provided a shovel which may in some respects 20 correspond to pulling shovels heretofore used and the shovel is provided with automatic means permitting it to load even up to the farther walls of the oven and will withdraw the coke loaded on the shovel and 25 ultimately dump it onto the usual conveyer provided along the front of the oven, beehive ovens being customarily arranged in rows with conveyers for receiving the withdrawn coke and carrying it to a suitable 30 point for disposition.

The device may be in form similar to an ordinary shovel in that it is so constructed that it may be shoved by suitable mechanism under the mass of coke in the oven, breaking 35 up the coke, and the body of the shovel is provided with a rockable plate forming the bottom of the shovel and so arranged that, when the shovel is withdrawn from the oven, the plate will overbalance and dump 40 whatever may be on it. Furthermore, the shovel is provided with pivoted wings so arranged that on forcing the shovel into the mass of coke in the oven the mass will ride over the wings and fall back of the shovel, 45 while the wings, on withdrawing the shovel, act as an abutment pulling the coke, which has ridden over the wings, out through the door of the oven. A few operations of the shovel effect the cleansing of the oven from 50 coke as thoroughly as the same operation may be performed by hand and more expeditiously, the pulling and cleaning occurring together. This does away with the necessity of hand labor for cleaning purposes and 55 therefore correspondingly shortens and cheapens the operation, permitting the oven

to be recharged in much less time than heretofore.

The invention will be best understood from a consideration of the following detailed description taken in connection with the accompanying drawings forming part of this specification, with the understanding, however, that the invention is not confined to any strict conformity with the showing 60 of the drawings but may be changed and modified so long as such changes and modifications mark no material departure from the salient features of the invention as expressed in the appended claims. 65

In the drawings:—

Figure 1 is an elevation of a pulling and cleaning structure in position to start operations on the coked mass in an oven, such oven, and a receiving conveyer associated 75 therewith being shown in vertical section.

Fig. 2 is a plan view of the pulling shovel.

Fig. 3 is a rear elevation of the shovel with the operating bar in cross section.

Fig. 4 is a front elevation of the shovel. 80

Fig. 5 is a longitudinal section on the line 5—5 of Fig. 4.

Referring to the drawings, there is shown a small portion of a bee-hive coke oven 1 having a door opening 2, a floor 3 and 85 hearth plate 4, these parts all being of customary type. It is usual to arrange bee-hive ovens in rows or batteries with a track along the fronts for the accommodation of apparatus and such track is indicated at 5 in Fig. 90

1. Moreover, it is also customary to provide a conveyer along the front of the ovens between the track and the ovens, such conveyer being indicated at 6. For the purpose of pulling the ovens there is provided a truck 95 7 to run upon the track 5 and this truck carries suitable mechanism including a pulling bar 8. With respect to the parts so far referred to the usual practice may be followed in construction and operation and, 100 hence, no special description or any particular showing of the parts is deemed necessary.

Carried by the bar 8 is a ram shovel 9 shown in side elevation in Fig. 1, but for 105 the details of construction reference will be had more particularly to Figs. 2 to 5 inclusive. The shovel comprises a three-sided frame made up of an end bar 10 and side bars 11, the end of the frame remote from the bar 10 being open. The free or forward ends of the bars or legs 11 of the frame 9 have

outstanding extensions or toe portions 12 tapering toward their outer extremities both from the front sidewise and from the top downwardly, it being understood that the shovel is moved back and forth along the floor of the oven in a substantially horizontal plane. The front edges 13 of the toes 12 are rounded and relatively sharp at their bottom edges and slant upwardly to a rear edge 14 merging into the tops of the arms 11, which latter increase in height from front to rear. Where the toes 12 extend laterally beyond the sides 11 they form shoulders 15 contributing to the pulling effect of the shovel when withdrawn from the oven, while the slanting faces of the toes and the relatively sharp front edges thereof facilitate the entrance of these parts of the shovel under the body of coke, indicated at 16 in Fig. 1.

Extending across the space between the sides or legs 11 immediately to the rear of the toes 12 is a pivot bar or rod 17 traversing the legs 11 and projecting beyond the outer edges thereof where the bar may be held to the shovel frame by cotter pins 18^a or in any other appropriate manner, these pins being well protected from damage by coke because arranged to the rear of the toes 12 and below the tops thereof. Mounted on the rod 17 is a plate 18 freely fitting between the legs 11 and extending from the end bar 10 to the front of the toes 12 at which latter point the plate has a forward curved slanting edge 19. The plate 18 increases in thickness from front to rear and is formed at the front edge 19 with an upstanding rib 20 dropping back to the level of the corresponding portion of the plate. Along the line of the rod 17 the plate has a double slanting rib 21 extending crosswise thereof and strengthening the plate where traversed by the rod as well as constituting a retarder for coke on the plate, preventing such coke from sliding off.

The bar 10 between the legs 11 has a slanting portion 22 and the front edge of the bar 10 below the slanting portion 22 is provided with a stop lug 23 which may be of triangular form, while the plate 18 has a top surface rib 24 extending crosswise of the rear edge of the plate and provided with a notch 25 to receive the lug 23.

Extending rearwardly from the central portion of the bar 10 is a socket 26 to receive the bar 8, the bar being made fast in the socket by bolts 27 or in other appropriate manner. Formed on the rear face of the bar 10 are ears 28 flanked by other ears 29 on a wing member 30 having a recessed portion 31 to straddle the socket member 26. The ears 28 and 29 are hinged together by pins 32 and the wing structure has a range of rocking movement about its pivots 32 from the rear face of the bar 10

to lugs 33 rising from the tops of the sides of the socket 26. When the wing structure is in engagement with the bar 10 it stands approximately upright and when in engagement with the lugs 33 it slants rearwardly at a considerable angle, the two positions of the wing structure being shown in dotted and full lines respectively in Fig. 5.

The plate 18 forming a rockable bottom to the shovel has a constant tendency to 75 gravitate toward a pendant position raising the front end and dropping the rear end, as indicated in dotted lines in Fig. 5.

With the structure described, the shovel is forced under the mass 16 of coke which 80 is lifted and more or less broken up by the slanting edge 19 of the plate 18 and the slanting edges 13 of the toes 12. The coke rides onto the plate 18 and is continuously lifted because of the slanting top face thereof and is, furthermore, lifted and broken by the slanting surfaces of the toes 12 and the slanting tops of the bars or legs 11 of the main frame of the shovel. Portions of the broken up coke fall upon the plate 18 90 and the latter moves thereunder until the coke ultimately rides over the rib 24, slanting edge 23 and onto the end bar 10 to finally find its way to the wings 30 which at this time bear against the lugs 33 and 95 are thereby held in a rearwardly slanting position. As the shovel is forced deeper into the mass of coke the disturbed and broken coke falls over the top of the wings 30 and drops behind the advancing shovel. 100 Some of the coke also passes over the toes 12 and falls behind the shoulders 14.

When the shovel has been forced deep enough into the coke the direction of movement is reversed, whereupon, the coke at 105 the rear of the shovel engages the wings and the latter are brought to an upright position against the bar 10 so that the coke being engaged by an upright abutment formed by the wings is drawn out of the 110 oven door and ultimately reaches the conveyor 6. The load of coke carried by the dumping plate 18 moves with the shovel through the oven door until the pivot pin 17 has approached the edge of the hearth 4 115 closely enough to permit the mass of coke on the rear portion of the dumping bottom plate 18 to overbalance the front edge thereof, whereupon, the plate will tip so that its load will readily gravitate onto the conveyor. The shovel is again introduced into the oven and withdrawn therefrom and the operation is repeated as often as needful to extract or pull the coke, while that coke carried by the plate 18 represents, especially toward the end of the pulling operation, those parts of coke charge which heretofore could only be removed by manual operation.

The actuating mechanism for the shovel 130

is of the ordinary type used for known forms of pulling shovels and is capable of moving the shovel to any part of the interior of the oven. The curvature of the front 5 of the shovel may correspond to the interior curvature of the oven so that it may reach practically to the walls of the oven. This permits the shovel to scoop up all or practically all loose particles beyond the 10 reach of the pulling part of the shovel so that the part of the shovel carrying the plate 18 is in effect a cleaning shovel and operates in conjunction with the pulling part of the shovel. This makes it possible 15 to combine the pulling and cleaning operations, thus materially shortening the time needed to discharge the oven ready for a fresh charge.

The toes 12 with their shoulders 15 form 20 efficient parts of the shovel in the cleaning operation. When the shovel is pulled out of the oven the toes 12 clean the coke from the jambs and the walls of the oven. The dumping bottom together with the laterally extended toes of the body of the shovel thoroughly clean the oven so that it is ready to 25 be recharged and eliminates the necessity of a workman entering the oven to remove material quantities of coke left in the oven by 30 other forms of shovels.

What is claimed is:—

1. A shovel for pulling coke from coke ovens, provided with a freely tiltable bottom having its underface, where designed to engage 35 the floor of the oven, in one plane.

2. A shovel for pulling coke from coke ovens, provided with a pulling bar at its rear end, and having a dumping bottom pivotally mounted near the front end and overbalanced 40 at its rear end, said dumping bottom when outside of the oven freely gravitating at all times to a pendant position.

3. A shovel for pulling coke from coke ovens, provided with pulling means at its 45 rear end, and a dumping bottom having a substantially flat bottom face, and an inclined beveled front edge above the plane of the bottom face and also having its top surface inclined rearwardly.

50 4. A shovel for pulling coke from coke ovens, provided at the rear end with pulling means, and a dumping bottom pivotally mounted near its front end transversely of the line of travel of the shovel and free at its rear end to gravitate to a pendant position, the underface of the dumping bottom being in substantially one plane and movable when in the oven into the plane of the lower face of the body of the shovel.

60 5. A shovel, for pulling coke from coke ovens, provided with a dumping bottom pivotally mounted near its front end transversely of the line of travel of the shovel and free at its rear end to gravitate to a pendant position, the front end of the shovel includ-

ing the bottom thereof being beveled and the top surface of the bottom portion and body of the shovel inclining rearwardly.

6. A shovel for pulling coke from coke ovens, comprising a body portion with pulling means at the rear end, and a bottom portion pivotally mounted near its front end to the body of the shovel and free at all times to gravitate at its rear end to a pendant position when the shovel is pulled from the oven. 70

7. A shovel, for pulling coke from coke ovens, comprising a body portion, and a bottom portion pivotally mounted near its front end in the body portion to move on an axis 80 transverse of the line of travel of the shovel, the bottom portion having a beveled front rib and another beveled rib on its top surface over the pivotal axis.

8. A shovel, for pulling coke from coke ovens, comprising a body portion, and a bottom portion pivotally mounted near its front end in the body portion to move on an axis transverse of the line of travel of the shovel, the bottom portion having a beveled front 90 rib and another beveled rib on its top surface over the pivotal axis, the top surface of the bottom portion inclining rearwardly and terminating at the rear edge in a rising beveled rib. 95

9. A shovel, for pulling coke from coke ovens, comprising a body portion, and a bottom portion pivotally mounted near its front end in the body portion to move on an axis transverse of the line of travel of the shovel, the bottom portion having a beveled front rib and another beveled rib on its top surface over the pivotal axis, the top surface of the bottom portion inclining rearwardly and terminating at the rear edge in a rising 100 beveled rib, and the body of the shovel having a stop member in the path of the rear end of the bottom of the shovel to prevent the latter from rising to a greater height than level position when the shovel is within 105 the coke oven. 110

10. A shovel, for pulling coke from coke ovens, having a body portion in the form of a frame open at and inclining rearwardly from the front end, and a dumping bottom 115 within the frame and transversely pivoted to the frame near the front end.

11. A shovel for pulling coke from coke ovens, having a body portion in the form of a frame open at the front end, a pulling bar 120 at the rear end of the body portion, and a dumping bottom within the frame and transversely pivoted thereto near the front end, said frame having the side members rising gradually from front to rear to a greater 125 height than the bottom.

12. A shovel for pulling coke from coke ovens, comprising a body portion in the form of a frame open at the front, and a dumping bottom mounted in the frame to gravitate to 130

1. A pendant position and of less height than the frame, said shovel having its bottom surface in substantially one plane, its forward end beveled to provide an entering edge, and the top surfaces inclining rearwardly with respect to the bottom surface.
2. A shovel, for pulling coke from coke ovens, comprising a body portion in the form of a frame open at the front with the forward ends of the side members of the frame laterally expanded and having the top surfaces inclined rearwardly and formed with rear shoulders where projecting laterally from the sides of the frame, and a bottom portion located between the sides of the frame and pivoted on a transverse axis near the front of the bottom portion to gravitate to a pendant position.
3. A shovel, for pulling coke from coke ovens, comprising a body portion in the form of a frame open at the front with the forward ends of the side members of the frame laterally expanded and having the top surfaces inclined rearwardly and formed with rear shoulders where projecting laterally from the sides of the frame, and a bottom portion located between the sides of the frame and pivoted on a transverse axis near the front of the bottom portion to gravitate to a pendant position, said body portion having a beveled front edge and a transverse beveled rib located over the pivotal axis of the bottom.
4. A shovel, for pulling coke from coke ovens, comprising a body portion in the form of a frame open at the front with the forward ends of the side members of the frame laterally expanded and having the top surfaces inclined rearwardly and formed with rear shoulders where projecting laterally from the sides of the frame, and a bottom portion located between the sides of the frame and pivoted on a transverse axis near the front of the bottom portion to gravitate to a pendant position, said body portion having a beveled front edge and a transverse beveled rib located over the pivotal axis of the bottom, the side members of the frame and the top surface of the bottom inclining rearwardly and the rear edge of the bottom and front edge of the rear member of the frame also inclining rearwardly.
5. A shovel, for pulling coke from coke ovens, comprising a frame open at the front end, with the side members of the frame having lateral expansions beveled toward the front and sides and shouldered at the rear, and a dumping bottom within the frame having its axis of dumping located near the front of the bottom and of the frame and having its front edge inclined rearwardly, with the front edges of both the bottom member and the front ends of the side members of the frame rounded laterally of the shovel.
6. A shovel for pulling coke from coke ovens, comprising a body member in the form of a frame open at the front and having the sides of the frame provided with outstanding extensions, and a dumping bottom mounted in the frame between the sides thereof.
7. A shovel for pulling coke from coke ovens, comprising a frame open at the forward end with the sides or legs of the frame having lateral extensions at their forward ends, a pulling bar at the rear end of the frame, and a dumping bottom pivotally mounted between the sides or legs of the frame and extending to the front of, said frame.
8. A shovel for pulling coke from coke ovens, comprising a frame open at the forward end and provided with a dumping bottom, the sides of the frame at their forward ends having outstanding extensions or toe portions tapering toward their outer extremities both from the front sidewise and from the top downwardly.
9. A shovel for pulling coke from coke ovens, comprising a frame open at the forward end and provided with a dumping bottom reaching to the forward end of the frame and pivotally mounted therein, the sides of the frame having laterally outstanding extensions or toe portions provided with shoulders at the rear.
10. A shovel for pulling coke from coke ovens provided with lateral extensions at the forward end, whereby said forward end of the shovel is of greater spread than the body of the shovel.
11. A shovel for pulling coke from coke ovens having lateral extensions at the forward end, whereby the spread of the shovel at the forward end is greater than the spread of the body of the shovel, and said shovel being provided with a dumping bottom extending to the forward end thereof.
12. A shovel for pulling coke from coke ovens, comprising a frame open at the forward end and there provided with side extensions, the frame increasing in height from the forward end toward the rear end, a dumping bottom for the frame mounted in and between the sides thereof, and pivotally mounted wings at the rear of the body member and rising at all times to a greater height than the body member and movable between an upright and a rearwardly slanting position, whereby coke in a coke oven underridden by the shovel is caught, on withdrawing the shovel from the oven, by the pivotally mounted wings, and is also caught upon the dumping bottom for discharge when the shovel is withdrawn to the front of the oven, and coke passing over the side extensions is withdrawn from the oven thereby.
13. A shovel for pulling coke from coke ovens, comprising a frame open at the forward end with the sides or legs of the frame having lateral extensions at their forward ends, a pulling bar at the rear end of the frame, and a dumping bottom pivotally mounted between the sides or legs of the frame and extending to the front of, said frame.
14. A shovel for pulling coke from coke ovens, comprising a frame open at the forward end and provided with a dumping bottom, the sides of the frame at their forward ends having outstanding extensions or toe portions tapering toward their outer extremities both from the front sidewise and from the top downwardly.
15. A shovel for pulling coke from coke ovens, comprising a frame open at the forward end and provided with a dumping bottom reaching to the forward end of the frame and pivotally mounted therein, the sides of the frame having laterally outstanding extensions or toe portions provided with shoulders at the rear.
16. A shovel for pulling coke from coke ovens, comprising a frame open at the forward end and there provided with side extensions, the frame increasing in height from the forward end toward the rear end, a dumping bottom for the frame mounted in and between the sides thereof, and pivotally mounted wings at the rear of the body member and rising at all times to a greater height than the body member and movable between an upright and a rearwardly slanting position, whereby coke in a coke oven underridden by the shovel is caught, on withdrawing the shovel from the oven, by the pivotally mounted wings, and is also caught upon the dumping bottom for discharge when the shovel is withdrawn to the front of the oven, and coke passing over the side extensions is withdrawn from the oven thereby.
17. A shovel for pulling coke from coke ovens, comprising a frame open at the forward end and provided with side extensions, the frame increasing in height from the forward end toward the rear end, a dumping bottom for the frame mounted in and between the sides thereof, and pivotally mounted wings at the rear of the body member and rising at all times to a greater height than the body member and movable between an upright and a rearwardly slanting position, whereby coke in a coke oven underridden by the shovel is caught, on withdrawing the shovel from the oven, by the pivotally mounted wings, and is also caught upon the dumping bottom for discharge when the shovel is withdrawn to the front of the oven, and coke passing over the side extensions is withdrawn from the oven thereby.
18. A shovel for pulling coke from coke ovens, comprising a frame open at the forward end with the sides or legs of the frame having lateral extensions at their forward ends, a pulling bar at the rear end of the frame, and a dumping bottom pivotally mounted between the sides or legs of the frame and extending to the front of, said frame.
19. A shovel for pulling coke from coke ovens, comprising a frame open at the forward end and provided with a dumping bottom, the sides of the frame at their forward ends having outstanding extensions or toe portions tapering toward their outer extremities both from the front sidewise and from the top downwardly.
20. A shovel for pulling coke from coke ovens, comprising a frame open at the forward end and provided with a dumping bottom reaching to the forward end of the frame and pivotally mounted therein, the sides of the frame having laterally outstanding extensions or toe portions provided with shoulders at the rear.
21. A shovel for pulling coke from coke ovens provided with lateral extensions at the forward end, whereby said forward end of the shovel is of greater spread than the body of the shovel.
22. A shovel for pulling coke from coke ovens having lateral extensions at the forward end, whereby the spread of the shovel at the forward end is greater than the spread of the body of the shovel, and said shovel being provided with a dumping bottom extending to the forward end thereof.
23. A shovel for pulling coke from coke ovens, comprising a frame open at the forward end and there provided with side extensions, the frame increasing in height from the forward end toward the rear end, a dumping bottom for the frame mounted in and between the sides thereof, and pivotally mounted wings at the rear of the body member and rising at all times to a greater height than the body member and movable between an upright and a rearwardly slanting position, whereby coke in a coke oven underridden by the shovel is caught, on withdrawing the shovel from the oven, by the pivotally mounted wings, and is also caught upon the dumping bottom for discharge when the shovel is withdrawn to the front of the oven, and coke passing over the side extensions is withdrawn from the oven thereby.
24. A shovel for pulling coke from coke ovens, comprising a frame open at the forward end with the sides or legs of the frame having lateral extensions at their forward ends, a pulling bar at the rear end of the frame, and a dumping bottom pivotally mounted between the sides or legs of the frame and extending to the front of, said frame.

ovens, comprising a frame open at the forward end and there provided with side extensions, the frame increasing in height around the forward end toward the rear 5 end, a dumping bottom for the frame mounted in and between the sides thereof, and pivotally mounted wings at the rear of the body member and rising at all times to a greater height than the body member and 10 movable between an upright and a rearwardly slanting position, whereby coke in a coke oven underridden by the shovel is caught, on withdrawing the shovel from the oven, by the pivotally mounted wings, and 15 is also caught upon the dumping bottom for discharge when the shovel is withdrawn to the front of the oven, and coke passing over the side extensions is withdrawn from the oven thereby, the wings extending across 20 the rear of the shovel as a continuous member and located wholly back of the rear of the body member of the shovel.

25. A shovel, for pulling coke from coke ovens, comprising a frame open at the front and having a socket projecting from the rear for the attachment of the shovel to an operating bar, said frame having side members with their upper surfaces slanting rear-

wardly and terminating at the front in lateral projections beveled forwardly and 30 rounded at the front, a dumping bottom located within the frame and extending to the front thereof and having a pivotal connection with the sides of the frame adjacent to the side extensions, said bottom having a 35 beveled rib at the front rising above the top surface of the bottom and rounded laterally, with the top surface of the bottom provided with another beveled rib rising therefrom above the pivotal axis and said top surface 40 inclining rearwardly, and with the bottom member of less height than the sides and rear of the frame, and a wing structure pivotally mounted at the rear of the frame and extending across the frame, said wing structure 45 rising above the top of the frame and movable on a transverse axis from an upright position to a rearwardly inclined position.

In testimony, that I claim the foregoing 50 as my own, I have hereto affixed my signature.

THOMAS P. RUANE.
